UNITED STATES PATENT OFFICE.

WALTER P. KELLOGG, OF SYRACUSE, NEW YORK.

DESIGN FOR A FEED-BOX.

SPECIFICATION forming part of Design No. 22,400, dated May 2, 1893.

Application filed April 5, 1893. Serial No. 469,208. Term of patent 14 years.

To all whom it may concern:

Be it known that I, WALTER P. KELLOGG, of Syracuse, in the county of Onondaga, in the State of New York, have invented a new and 5 useful Design for Feed-Boxes, of which the following, taken in connection with the accompanying drawings, is a full, clear, and exact description.

Figure 1, shows a front view of the box.
Fig. 2, shows a side view thereof.

The leading feature of my design consists in the upper part being substantially rectangular and the lower portion being increased in size at its upper end and reduced and contracted at its lower end.

A, is the upper portion of substantially rectangular shape and having the cornice —a—. B, is the lower part enlarged as shown at —b— and contracted at its lower end, as shown at —c— to substantially circular form. 20

What I claim, and desire to secure by Letters Patent, is—

The design for a feed-box, substantially as herein described and shown.

In witness whereof I have hereunto set my hand this 3d day of April, 1893.

WALTER P. KELLOGG.

In presence of—

C. B. KINNE,

HOWARD P. DENISON.
